GOLF BAG CART

William J. Babcock, Lafayette, Calif., and Jack R. Goodrich, Minoa, N.Y., assignors to Babcock Mfg. Co., Oakland, Calif., a corporation of California

Filed July 3, 1962, Ser. No. 70,783

Term of patent 14 years

(Cl. D14—3)

Fig. 1

We claim:

The ornamental design for a golf bag cart, as shown.
